C. FASOLDT.
Clock Escapement.

No. 22,791.

Patented Feb 1, 1859.

Charles Fasoldt.

UNITED STATES PATENT OFFICE.

CHARLES FASOLDT, OF ROME, NEW YORK.

ESCAPEMENT FOR TIMEKEEPERS.

Specification of Letters Patent No. 22,791, dated February 1, 1859.

To all whom it may concern:

Be it known that I, CHARLES FASOLDT, of Rome, Oneida county, State of New York, have invented a new and useful Improvement in Lever-Escapements; and I hereby declare that the following is a full and exact description of the improvement aforesaid, reference being had to the accompanying drawings, making part of this specification.

A is a propelling and detent wheel connected.

B, B, B, is the balance wheel so drawn for the purpose of showing the different positions of the detent lever when in actual operation.

L is a straight detent lever having its center of motion C between and in a right line drawn from center to center of the balance 20 and escapement wheels.

H is a hook attached to the lever with the like center of motion. One extremity of the lever terminates in a fork F vibrating in the partial rotation of the balance wheel in a 25 manner well understood. The other extremity of the lever has a peculiar form, such that a tooth of the escapement wheel may at stated periods rest against it and be readily unlocked so as again to allow the 30 rotation of the wheel.

In order to a better comprehension of the means I employ to produce a simple and perfect isochronal movement I will describe the operation having reference to the three 35 different positions numbered 1, 2 and 3.

In Figure 1, the lever will be seen in one limit of its movement with a tooth of the escapement wheel resting locked against its extremity: next will succeed the reaction of the 40 balance wheel and the impulse therefrom in

the direction indicated by the arrow dislodges the other extremity of the lever and throws it in advance of the tooth it was just restraining so that it now takes the position exhibited in No. 2. The lever is now moved 45 in turn by the escapement wheel and is carried to the other limit of its motion as shown in Fig. 3. The detent hook at the center of the lever here locks the escapement wheel awaiting the reverse motion of the balance 50 wheel to return the opposite end of the lever to the position it occupied when the description commenced.

The simplicity and perfection of my arrangement will thus be made apparent to all 55 skilled in this branch. I detain the escapement wheel by its meeting the lever at stated periods so that the point of the tooth of the wheel rests against the point or end of the lever and by a single impulse it is disengaged or unlocked and thrown in advance 60 of the tooth when the lever is in turn moved by the wheel to its other limit so that the angular movement with reference to the escapement and detent wheel enables me to 65 avail of the direct action through the constant power of the former wheel dispensing with all reverse action of the lever and materially diminishing the friction thus rendering the movement less complicated and 70 less liable to need repair or regulation.

What I claim as my invention is—

The employment of a straight lever and collateral hook in the position and form indicated and described.

CHARLES FASOLDT.
